RAILWAY TRUCK

Harry M. Pflager, St. Louis, and Edwin C. Jackson, Clayton, Mo., assignors to General Steel Castings Corporation, Granite City, Ill., a corporation of Delaware

Application December 9, 1940, Serial No. 369,206

19 Claims. (Cl. 105—182)

The invention relates to railway rolling stock, and more particularly to swivel trucks for use in high speed service. In recent years there has been a marked tendency toward light weight car bodies which, with the higher speeds at which trains are being operated, require trucks of light weight and good riding qualities having spring arrangements between the axles and the car body which permit carrying only a minimum amount of the energy in vertical forces or shocks to the car body. At the same time, it is desirable to provide for lateral movement between the car body and the truck wheels so that irregular track or curved track will cause a minimum amount of lateral shocks between the car body and the truck.

One object of the present invention is to provide a simple and light weight truck which will give good riding qualities by transmitting a minimum amount of vibrations and shocks to the car body due to the upward or downward movement of the wheels and axles relative to the car body, when running over rough or irregular track, and by providing at the same time a lateral motion arrangement which will prevent transmission of excessive vibrations to the car body and side sway of the car body.

Another object is to provide a spring arrangement to control the vertical movement of the journal boxes relative to the truck frame so that the spring action will produce good riding qualities and be quick acting to keep the wheels on the rail so as to provide safe riding qualities.

Another object is to dampen oscillations of quick acting springs so as to promote the easy riding qualities of the truck.

A more detailed object of the invention is to simplify and lighten the truck by omitting equalizers without sacrificing the easy riding qualities produced by this well known feature of construction.

These and other detailed objects as will appear below are attained by the structures illustrated in the accompanying drawings, in which—

Figure 1 is a top view of one longitudinal half of a four-wheel truck.

Figure 2 is a side elevation of the same.

Figures 3 and 4 are detail horizontal sections taken on the corresponding section lines of Figure 2.

Figure 5 is a detail vertical longitudinal section taken on the line 5—5 of Figure 1.

Figure 6 is an end view looking towards the right hand end of Figures 1 and 2.

Figure 7 is a vertical transverse section looking

in the same direction and taken on the line 7—7 of Figure 2.

Figure 8 is an end view looking in the opposite direction towards the left hand end of Figures 1 and 2.

Figures 9 and 10 correspond generally to Figures 1 and 2 but illustrate another form of the invention and the intermediate portion of the truck is broken away to make possible use of a larger scale, and in Figure 9 a portion of this structure is sectioned horizontally along the line 9—9 of Figure 10.

Figure 11 is an end view looking toward the right hand end of Figures 9 and 10.

Figures 12 and 13 are vertical transverse sections looking in the same direction and taken on the corresponding section lines of Figure 10.

Figure 14 is an end view looking in the opposite direction towards the left hand end of Figures 9 and 10.

Figures 15 and 16 correspond to Figures 9 and 10 but illustrate another form of the invention.

Figures 17, 18, 19 and 20 correspond to Figures 11, 12, 13 and 14, respectively, but illustrate the structure shown in Figures 15 and 16, Figures 18 and 19 being taken upon the corresponding section lines of Figure 16.

The truck shown in Figures 1—8 includes wheels 1 mounted on axles 2, which carry roller bearing journal boxes 3 in the usual manner. The truck frame includes wheel pieces 4 and depending pedestal legs 5 which slidably receive the journal boxes, the latter being flanged at 6 (Figure 3) to limit lateral movement of the frame relative to the boxes, wheels and axles. Flanges 6 and the adjacent portions of pedestal legs 5 are provided with the usual wear plates 7.

Pivotedly suspended from each journal box are links 8 at opposite sides of the axle. Brackets 9 project outwardly from pedestal legs 5, and brackets 9 of each pair of legs journal a shaft 10 extending longitudinally of the truck below the level of the axle centers. Crank arms 11 on each shaft 10 extend inwardly and have their inner ends pivotally connected to the lower ends of links 8.

Torsion rods 12 and 13 are journalled in brackets 14 on the ends of the truck frame wheel piece. The inner rod 12 has a crank arm 15 (Figure 6) secured to its right hand end. An anchoring eye-bolt 16 is pivotally connected to the lower end of arm 15 and extends through a lug 17 on the end of the truck frame where it is adjustably secured by nuts 18. The opposite end of torsion rod 12 has a depending crank arm

19 (Figure 8) keyed thereon and the lower end of this arm is pivotally connected by link 20 to the upper end of a crank arm 21 keyed to the outer end of the corresponding shaft 10.

Torsion rod 18 is similarly anchored by eye-bolt 22 to lug 23 at the left hand end of the frame (Figure 8) and is similarly connected by crank arm 24, link 25 and crank arm 26 to shaft 10 at the other end of the truck. Preferably, each of shafts 10 has an additional bearing in a bracket 27 depending from the end portions of the wheel piece.

With this arrangement, the truck frame and its load is yieldingly supported from the journal boxes by links 8, shafts 10 and torsion rods 12 and 18, the yielding resistance of the latter to torque holding the crank arms at the approximate angles shown in the drawings. The arrangement of the spaced links 8 and spaced bearings for shafts 10 prevent the rotation of the boxes about the axle journals and uneven thrust between the journal boxes and the pedestal legs. Any upward thrust on one link at one side of a box would be resisted by the downward thrust on the link at the other side of the box.

The truck frame also includes spaced transoms 30 between which is a truck bolster 31 arranged for lateral movement in the frame by means of swing hangers 32 suspended from the truck frame and supporting a cross bar 33 at their lower ends, which carries elliptic springs 34 either directly or through a spring plank in a manner familiar to those skilled in the art. The bolster will swing laterally when the truck rides over curved track or at any other time when there is a substantial transverse force transmitted between the truck and the car body which would be mounted upon the truck through the usual center plate 35.

The torsion rods for each journal box provide a quick acting spring arrangement between the journal box and the truck frame to keep the wheels on the rail and they act as a primary set of springs to cushion and absorb shocks and vibrations, so that a limited amount of the vibrations and a limited amount of the energy of the shocks is transmitted to the truck frame and then to the car body.

The bolster elliptic springs comprise a secondary set of springs which provide a greater amount of vertical movement between the car body and the truck to cushion and absorb the heavier vertical shocks which are applied to the truck. They also act as a snubbing means, due to the friction between their leaves when being deflected, to prevent synchronization of vibrations of the torsion springs and the elliptic springs, thus resulting in a minimum amount of undue recoil action or bouncing of either or of both sets of springs.

By providing auxiliary shafts 10 to transfer the load to the torsion rods located above the journal boxes, it is possible to provide longer torsion rods than would be possible if arms 11 were directly on the torsion rods and the latter were located below the axle centers. This arrangement also provides for better road clearances than if the torsion rods were located below the axle centers and outwardly of the ends of the journal boxes.

The bearings for shafts 10 include detachable caps 36 which are readily removed to facilitate application and removal of shafts 10 with the crank arms 11, 21 and 26, and by disconnecting links 28 and 25, connecting these crank arms

to the torsion rods, the wheeled axles may be readily dropped from the truck.

The truck shown in Figures 9-14 includes wheeled axles, journal boxes and a truck frame provided with pedestals slidably receiving the journal boxes similarly to the arrangement described above, and it will be understood that the truck frame is provided with a load supporting bolster preferably of the lateral motion type previously referred to. Also the journal boxes pivotally support swinging links 40, corresponding to links 8, and the pedestal legs include outwardly extending brackets 41 corresponding to brackets 8 above.

The torsion rods 42 and 43 are journalled in all four brackets 41 and each is provided near one end with crank arms 44 and 45 respectively, extending inwardly with their inner ends pivotally connected to the lower ends of a corresponding pair of links 40 suspended from the journal boxes as links 8 previously described. The opposite end of each torsion rod is adjustably anchored to the truck frame by an individual crank arm 46 and 47 respectively and an eye-bolt 48 and 49 respectively.

This arrangement eliminates the auxiliary shafts embodied in the construction previously described and, therefore, simplifies the construction substantially. However, the effective length of the torsion rods is less than their overall length since their yielding torque must take place between the anchored end of the rod and the crank connected to the inner pedestal leg at the opposite end of the truck; whereas, in the arrangement previously described, the rod is free to yield about its axis throughout its entire length.

By placing the torsion rods 42 and 43 equal distances above and below the level of the lower end of links 40, the crank arms 45 and 46 are normally inclined at equal angles to the horizontal. This permits all of links 40 to be of equal length and provides for equal clearance between the pedestal tie bars 50 and the lower ends of the links or the outer ends of the arms.

The truck shown in Figures 15-20 includes wheeled axles, journal boxes, with pivotally suspended links 60, and a truck frame 61 generally similar to those previously described, and the truck load preferably is transmitted to the truck frame through a lateral motion bolster (not shown), as described in connection with the structure shown in Figures 1-8. As in the structure of Figures 9-14, the torsion rods 62 and 63 are journalled in brackets 64 extending outwardly from the truck frame, but the brackets are of different heights and the torsion rods are inclined from one end of the truck to the other instead of being horizontal. With this arrangement, the portion of each torsion rod opposite to the journal box to which it is connected is at the same level as the corresponding portion of the other torsion rod.

All of the arms 65 by which the rods are connected to link 60 are disposed at the same angle, preferably horizontal under the normal load, and if the arms 65 depart from the horizontal position their effective length will be maintained equal for all arms. In the arrangement shown in Figures 9-14, the effective length of the crank arms 44 and 45 are the same at the single normal position indicated. If the relative height of the journal boxes and truck frame departs in either direction from its normal position, the effective length of the arms on one torsion rod will be shortened as

the effective length of the arms on the other torsion rod will be lengthened.

However, the horizontal alignment of the brackets for each torsion rod facilitates machining of the bearings and the horizontal arrangement of the torsion rods presents a better appearance, and these factors may make this structure preferable to that shown in Figures 15-20 notwithstanding that possibly the action of the two rods would be more nearly equal in the construction shown in Figures 15-20.

Any of the constructions shown are adapted to attain one or more of the advantages set forth in the introductory portion of the specification, and it will be understood that the constructions may be varied otherwise than as described and that some features of the invention may be used without including necessarily all of the other features. The exclusive use of the different structures described and other modifications as may occur to those skilled in the art and embodying the spirit of the invention as expressed in the appended claims is contemplated.

What is claimed is:

1. In a railway truck, a wheeled axle, a journal box on said axle, links pivotally suspended at their upper ends from said box, a truck frame including a wheel piece positioned directly over said box and including a pedestal slidably receiving said box, and a torsion rod extending longitudinally of the truck and spaced from said wheel piece transversely of the truck and journalled on said frame and having a crank arm at one end portion with its outer end anchored to the swinging lower ends of said links, the opposite end portion of said rod being held against rotation relative to said frame, whereby said frame is spring supported from said box by the yielding of said rod to torque.

2. In a railway truck, spaced wheeled axles, journal boxes on said axles, a truck frame with pedestals slidably receiving said boxes, and a pair of torsion rods extending alongside of each other at one side of and longitudinally of the truck and journalled in said frame, each of said rods having a crank arm at one end portion with its outer end anchored to a respective one of said boxes and having its opposite end portion held against rotation relative to said frame, whereby said frame is spring supported from said boxes by the yielding of said rods to torque.

3. A railway truck as described in claim 1 which includes hangers suspended from the truck frame to swing laterally of the truck, and truck load supporting structure carried by said hangers and having elements projecting transversely of the truck beyond the frame, the torsion rod extending longitudinally of the truck above the level of said elements.

4. A railway truck as described in claim 1 in which the load supporting structure includes plural-leaf springs supported by the truck frame, and a bolster mounted on said springs, said springs providing a snubbing means to prevent synchronization of vibrations of the springs formed by the torsion rod.

5. A railway truck as described in claim 1 in which the springs formed by the torsion rod constitute a primary set of springs to cushion and absorb vertical shocks transmitted between the journal boxes and the truck frame, and the load supporting structure includes a bolster and elliptic springs supporting said bolster and constituting a secondary set of springs to provide smoother riding by further cushioning and ab-

sorbing the shocks which may otherwise be carried to the car body, said sets of springs also serving to dampen the total spring action.

6. In a railway truck, a wheeled axle, a journal box on said axle, a truck frame with a pedestal slidably receiving said box, a shaft journalled on said pedestal, and a torsion rod extending longitudinally of the truck and journalled near one end on the adjacent end portion of said frame and held at its other end against rotation relative to said frame, said shaft and rod being spaced apart transversely of their axes, individual crank arms on said shaft and torsion rod with their outer ends pivotally connected to each other, and a crank arm on said shaft with its outer end anchored to said journal box, whereby the weight of the truck frame and its load is yieldingly supported by the resistance of said rod to torque.

7. A railway truck as described in claim 6 in which the shaft journalled in the pedestal is located below the level of the axle center and the torsion rod is located above the axle center.

8. A railway truck as described in claim 6 in which the journal box anchorage for the end of the shaft crank arm comprises a link pivotally suspended from the journal box.

9. In a railway truck, spaced wheeled axles, journal boxes on said axles, a truck frame with pedestals slidably receiving said boxes, links pivotally suspended from said boxes to swing transversely of the truck, shafts each extending longitudinally of the truck abreast of a respective one of said boxes and journalled in said frame having crank arms pivotally connected at their ends to the lower ends of said links, and torsion rods journalled in said frame and each having one end anchored against rotation relative to an end of said frame and having a crank arm at its other end, there being another crank arm on the corresponding shaft, and a pivotal connection between said latter-mentioned crank arm and said rod crank arm.

10. A railway truck as described in claim 9 in which the torsion rods are located above the boxes and extend the full length of the truck and each is connected at one end to the associated shaft and at the other end is anchored to the truck frame.

11. A railway truck as described in claim 9 in which the anchorage between the truck frame and the end of each rod is adjustable to vary the height of the truck frame.

12. In a railway truck, a wheeled axle, a journal box on said axle, a truck frame with a pedestal slidably receiving said box, brackets extending outwardly from the legs of said pedestal, a shaft journalled in said brackets and having inwardly extending crank arms, links pivotally suspended from said journal box and pivotally connected to the inner ends of said arms, a torsion rod extending longitudinally of the truck and journalled in said frame and having a crank arm at one end portion, a crank arm on said shaft having its end connected to the end of said rod crank arm, the opposite end portion of said rod being held against rotation relative to said frame, whereby said frame is spring supported from said box by the yielding of said rod to torque.

13. In a railway truck, a wheeled axle, a journal box on said axle, a truck frame with a pedestal slidably receiving said box, brackets extending outwardly from the legs of said pedestal, a torsion rod extending longitudinally of

the truck and journalled in said brackets and having a crank arm near one end extending inwardly of the truck, a link pivotally suspended from said journal box with its lower end pivotally connected to said crank arm, the other end of said torsion rod being held against rotation relative to said frame, whereby said frame is spring supported from said box by the yielding of said rod to torque.

14. In a railway truck, spaced wheeled axles, journal boxes on said axles, a truck frame with pairs of depending pedestal legs slidably receiving said boxes, and a pair of torsion rods extending longitudinally of the truck and each journalled at least at one end in said pedestal legs below the centers of said axles and provided with crank arms at their other ends, the crank arm of one torsion rod being anchored at its outer end from the adjacent journal box and the crank arm of the other torsion rod being anchored at its outer end from the other journal box, the ends of said rods remote from the journal boxes from which their arms are supported being held against rotation relative to said frame, whereby said frame is spring supported from said box by the yielding of said rod to torque.

15. A truck as described in claim 14 in which the torsion rods are arranged one above the other and the crank arm on one rod is inclined downwardly toward the journal box and the crank arm on the other rod is inclined upwardly towards the journal box and the ends of the crank arms are pivotally suspended from the journal boxes by links of equal length.

16. A truck as described in claim 14 in which the torsion rods are arranged one above the other and are inclined to the horizontal longitudinally of the truck so that their end portions anchored to the journal boxes are at the same level.

17. A truck as described in claim 14 in which the supports for the torsion rod crank arms comprise links pivotally suspended from the journal boxes, and the torsion rods are arranged one above the other and are inclined to the horizontal so that the portions of the rods adjacent the journal boxes are at the same level, the crank arms on said rods normally extending horizontally and the suspension links therefor being of equal length.

18. A truck as described in claim 2 in which the torsion rods extend alongside of each other in the same general plane and at approximately the same level as the top of the truck frame, there being hangers suspended from the truck frame to swing laterally of the truck, and load-supporting structure carried by said hangers and including elements projecting transversely of the truck beyond said frame and beneath said torsion rods.

19. In a railway truck, a wheeled axle, a journal box on said axle, a link pivotally suspended at its upper end from said box, a truck frame including a wheel piece positioned directly over said box and including a pedestal slidably vertically on the box, a bracket projecting from said frame transversely of the truck, and a torsion rod extending longitudinally of the truck and positioned exteriorly of the frame wheel piece and pedestal and readily accessible from the side of the truck and journalled on said bracket and having one end portion anchored against rotation relative to the frame and having a crank arm on its other end portion connected to said link, whereby said frame is yieldingly suspended from said box by said links and by the resistance of said rod to torque.

H. M. PFLAGER.
EDWIN C. JACKSON.
